MACHINE FOR INSERTING PINS INTO A PERFORATED RIBBON

Harold Peasgood, Slough, England, assignor to Technicolor Corporation, Hollywood, Calif., a corporation of Maine

Application November 22, 1955, Serial No. 548,514

4 Claims. (Cl. 29—211)

This invention relates to a machine for inserting headed pins into a perforated ribbon and more particularly to a machine for mounting register pins in a pin-belt of the type used for registering cinematographic film. Ordinarily these pins have shanks which are shaped to fit the sprocket holes of film with flat heads which seat against the back side of the belt, each shank having an elongate cross-section with the short dimension extending lengthwise of the belt and the long dimension extending crosswise of the belt. The belt is perforated along each edge with perforations substantially the same shape and size as those of the pin shanks and pins are mounted in both rows of perforations. While the aforesaid short dimension may be the same in both rows of pins, the long dimension of the shanks of one row of pins is preferably less than that of the other row so as not to fill the film perforations transversely of the film.

Heretofore it has been proposed to feed the perforated ribbon past a pinning station intermittently and insert a single pin at each step, but this procedure has been slow and expensive. Objects of the present invention are to increase the rate of inserting the pins, to feed the ribbon continuously instead of intermittently, and to insert the pins in both rows concomitantly.

According to the present invention the machine comprises a carrier having a longitudinal row of seats for supporting the pins with their heads bearing on the seats and their shanks projecting therefrom, the spacing of the seats approximating that of the openings in the belt or other ribbon into which the pins are to be inserted, together with means for detachably holding the pins on their seats, means for feeding the ribbon to the carrier obliquely so that the shanks enter the openings and means for pressing the ribbon toward the carrier to seat the ribbon against the heads. The means for holding the pins on the seats preferably comprises a vacuum manifold in the carrier with ducts leading to the seats. The carrier is preferably in the form of a rotor having the aforesaid seats distributed in one or more circumferential rows about its periphery, in which case the ribbon is fed to the rotor tangentially. The pins may be supplied to the rotor in any suitable way, as by hand, but they are preferably fed automatically by the apparatus described and claimed in the copending application Serial No. 548,515 of John H. Francis filed on Nov. 22, 1955.

For the purpose of illustration a typical embodiment of the invention is shown in the accompanying drawings in which

Fig. 1 is a plan view of the machine;

Fig. 2 is a front elevation of the machine;

Fig. 3 is a section on line 3—3 of Fig. 1;

Fig. 4 is a section on line 4—4 of Fig. 3;

Fig. 5 is a section on line 5—5 of Fig. 3;

Fig. 6 is a section on line 6—6 of Fig. 4; and

Fig. 7 is a plan view of a typical pin for use in registering cinematographic films.

In the illustration the pins have flat circular bases 1 and shanks 2 for insertion through a ribbon R with the

2

heads of the pins seating against one side of the ribbon as shown in Fig. 4. As shown in Figs. 1 and 7 the shanks have an elongate cross-section with the short dimension extending lengthwise of the ribbon and the long dimension

5 extending crosswise of the ribbon. For use in registering cinematographic film the long dimensions of the shanks correspond to the long dimensions of the film perforations along one edge of the ribbon and along the other edge of the ribbon the long dimension of the shanks is somewhat 10 less so that they do not fill the film perforations crosswise of the film. In Figs. 1 and 2 the full-fitting pins are applied to the ribbon R along its left-hand margin and the smaller pins are applied to the ribbon along the right-hand margin.

15 According to the present invention the pins are placed in recessed seats 3 distributed in two circumferential rows around the periphery of a rotor 4 on shaft 5 with their heads fitting loosely in the seats and their shanks projecting radially from the rotor (Figs. 1, 2 and 3).

20 As shown in Fig. 3 the rotor turns in a counterclockwise direction, the pins are presented to it at the right-hand side and they are inserted into the ribbon at the top, the ribbon being fed tangentially to the rotor between a support 6 and a guide roller 7. While being carried by

25 the rotor the pins are held in their seats by vacuum means communicating with the seats through a pipe 8, manifold 9 and ducts 11, the manifold 9 being disposed in the stationary frame 12 and extending from the point where the pins are applied to the rotor to the point where they are inserted in the belt (Figs. 3 and 5). As the ribbon approaches the rotor tangentially the pins gradually enter the perforations in the ribbon which is backed by rollers 13 journaled in the support 14 which is mounted on the frame 12 by means of screws 16, the rollers having grooves 17 to accommodate the tips of the pin shanks as they are inserted through the ribbon.

30 After the ribbon has been applied to the pin shanks it is pressed against the pin heads by means of a roller 18 above the rotor, the roller having recesses 19 in its edges to accommodate the projecting tips of the pins. The roller 18 is driven by means of a crank 21 through a shaft 22, worm 23, worm wheel 24, and shaft 26 (Figs. 1, 2 and 4). To facilitate threading the ribbon between the rotor 4 and roller 18 the shaft 26 is journaled in blocks 27 and

35 28 which are mounted in recesses in the frame 12 by means of screws 29. By loosening the screws the shaft 26 may be tipped to the position shown in Fig. 4 where the ribbon may be inserted edgewise between the rotor and roller. The rotor shaft 5 is driven from the roller shaft 26

40 through gears 31 and 32. The gear 31 is attached to the shaft 26 through a collar 33, the gear 31 being secured to the collar by means of pins 34 extending through slots 36 in the collar and threading into the gear 31 (Figs. 4 and 6). To bring the roller 18 in synchronism with the

45 rotor 4, so that the projecting pin shanks will register with the recesses 19, the gear 31 is adjustable circumferentially of the collar 33 by means of a pin 37 rotatably mounted in the collar and having an eccentric portion 38 extending

50 into a radial slot 39 in the gear. By loosening the screws 34 and rotating the pin 37 the roller 18 may be brought into exact synchronism with the rotor 4, after which the screws 34 are tightened to hold the parts in synchronism. In lifting the shaft 26 for threading purposes, as illustrated

55 in Fig. 4 and as above described, the gear 31 may be left in mesh with the gear 32 so that the parts need not be thrown out of synchronism in threading the machine.

The pins may be applied to the rotor 4 by hand as the seats 3 arrive opposite the manifold 9 but they are preferably supplied by automatic means such as disclosed in the aforesaid application. In the illustration the aforesaid smaller pins are applied to the right-hand row of

seats 3 (Figs. 1 and 2) and the full-fitting pins are applied to the left-hand row of seats.

It should be understood that the present disclosure is for the purpose of illustration only and that this invention includes all modifications and equivalents which fall within the scope of the appended claims.

I claim:

1. For inserting into a ribbon having a row of openings, pins having shanks projecting through the openings with heads seating on one side of the ribbon around the openings, a machine comprising a support, movably mounted on the support a carrier having a row of seats for supporting said pins with their heads bearing on the seats and their shanks projecting therefrom, the spacing of the seats approximating that of the openings in the ribbon, means for detachably holding the pins on their seats, said row extending in a predetermined direction, means for moving the carrier in said direction, means for feeding the ribbon to the carrier synchronously with the carrier so that said shanks enter said openings sequentially, and means on said support for pressing the ribbon toward the carrier to seat the ribbon against said heads.

2. For inserting into a ribbon having a row of openings, pins having shanks projecting through the openings with heads seating on one side of the ribbon around the openings, a machine comprising a support, movably mounted on the support a carrier having a row of seats for supporting said pins with their heads bearing on the seats and their shanks projecting therefrom, the spacing of the seats approximating that of the openings in the ribbon, the carrier containing a vacuum manifold with ducts leading to said seats for detachably holding the pins on their seats, said row extending in a predetermined direction, means for moving the carrier in said direction, means for feeding the ribbon to the carrier synchronously with the carrier so that said shanks enter said openings sequentially, and means on said support for pressing the

ribbon toward the carrier to seat the ribbon against said heads.

3. For inserting into a ribbon having a row of openings pins having shanks projecting through the openings with heads seating on one side of the ribbon around the openings, a machine comprising a support, rotatably mounted on the support a rotor having on its periphery a circumferential row of seats for supporting said pins with their heads bearing on the seats and their shanks projecting radially, the circumferential spacing of the seats approximating that of the openings in the ribbon, means for detachably holding the pins on their seats, means for feeding the ribbon to the rotor tangentially so that said shanks enter said openings, and means on said support for pressing the ribbon toward the rotor to seat the ribbon against said heads.

4. For inserting into a ribbon having a row of openings pins having shanks projecting through the openings with heads seating on one side of the ribbon around the openings, a machine comprising a support, rotatably mounted on the support a rotor having on its periphery a circumferential row of seats for supporting said pins with their heads bearing on the seats and their shanks projecting radially, the circumferential spacing of the seats approximating that of the openings in the ribbon, the rotor containing a vacuum manifold with ducts leading to said seats for detachably holding the pins on their seats, means for feeding the ribbon to the rotor tangentially so that said shanks enter said openings, and means on said support for pressing the ribbon toward the rotor to seat the ribbon against said heads.
